PACKER FOR WELLS

Paul M. Rohrbaugh, Duncan, Okla., assignor to
 Halliburton Oil Well Cementing Company,
 Duncan, Okla.

Application July 12, 1937, Serial No. 153,088

11 Claims. (Cl. 166—12)

This invention relates to apparatus adapted for use in oil wells or the like, and more particularly to packers and means for releasably securing the same to the casing of a well.

5 It is often desirable to fix and seal a valve or other structure to the casing of an oil well. For example, where a well is to be cemented by forcing cement slurry under pressure down into the well through drill pipe or tubing and into the 10 formation of the well, particularly in connection with what is known as a "squeeze job", it is desirable to provide means at the bottom of the tubing which can be fixed to the casing, thus holding the tubing in place against the fluid pressure of the cement. It is also desirable in such 15 a case to provide a packer or other sealing means around the tubing so as to prevent the passage of cement slurry upwardly between the tubing and the casing.

20 It is an object of the present invention to devise novel means for temporarily setting a packer on tubing or drill pipe in a well, secure the packer in place and hold the same against movement with respect to the casing.

25 It is a further object of the invention to provide novel means for removing a packer or securing means fastened to the casing in an oil well.

It is another object of the invention to devise 30 apparatus for retaining cement or other fluid under high fluid pressure in place in an oil well and to so arrange the apparatus that it can be readily removed from the well after it has accomplished its purpose.

It is a further object of the invention to devise 35 novel means for setting and releasing slips or other holding means in the casing of an oil well.

It is still a further object of the invention to provide a mechanism adapted for use with a 40 packer or with slips and in which the slips are so connected to the packer and operating mechanism that toggle action is used in the setting and releasing of the slips.

Other objects and advantages reside in certain 45 novel features of the arrangement and construction of parts as will be more apparent from a consideration of the following description taken in connection with the accompanying drawings, in which:

50 Figure 1 is a vertical cross-sectional view of a packer assembly constructed in accordance with the principles of the present invention and showing the parts in the relative positions which they occupy while the assembly is being lowered into an oil well;

55 Figure 1A is a view in perspective of fragmen-

tary portions of latching means shown in Figure 1.

Figure 2 is a vertical cross-sectional view of the apparatus shown in Figure 1 but illustrating the relative positions of the parts after the slips have been set in the casing of an oil well but before the packer has been expanded into engagement with the casing;

Figure 3 is a vertical cross-sectional view of the apparatus shown in Figure 1 but showing the parts in the relative positions which they occupy after the slips and packer have been set in the casing and during a cementing operation;

Figure 4 is a vertical cross-sectional view of the apparatus shown in Figure 1 but illustrating the relative positions after the cement has been placed in the well and hardened and after the slips have been released from engagement with the casing of a well; and

Figure 5 is a perspective view of one of the slips 20 employed in the arrangement of Figures 1 to 4, inclusive.

Figure 6 is a view in perspective of one of the upper links employed in the apparatus of Figures 1 to 4;

Figure 7 is a perspective view of a fragment of one of the lower links employed in the arrangement of Figures 1 to 4;

Figure 8 is a view in perspective of the control ring employed in the arrangement of Figures 1 to 4 with a portion of the latching sleeve connected thereto; and

Figure 9 is a view in perspective of a slotted nut employed in the arrangement of Figures 1 to 4.

Referring to the drawings in detail, it will be seen that in Figures 1 to 4 an oil well casing is illustrated at 11. Apparatus constructed in accordance with the present invention adapted to be secured to the casing to seal the lower portion from the upper portion thereof, may include a central tubular mandrel 12 which may be screw threaded on to the lower end of the drill pipe or tubing (not shown) in accordance with usual practice. The mandrel 12 extends practically 40 throughout the entire length of the packer assembly. It is provided with a swivel 13 at its lower end so as to form a connection with the lower shoe 14 of a packer 15. This packer may be of rubber or like material and constructed in 45 accordance with known practices. Usually, the lower shoe of such a packer is provided with a sleeve which extends upwardly inside the packer between it and the lower part of the operating mandrel. A sleeve of this nature is shown at 16 55

in the drawings. The packer 15 is also provided with an upper shoe 17 concentrically disposed with respect to the upper end of the sleeve 16.

Located above the packer and connected to the upper shoe 17 thereof is a set of slips designated 18. Any number of slips may be employed, but in the arrangement illustrated, four are contemplated. Each slip is provided with a number of outwardly and upwardly directed teeth 19 which are adapted to engage and bite into the casing 11 when the slips are forced outwardly radially into contact with the casing 11. Each slip 18 is connected to the upper shoe 17 by means of parallel links 20. The upper ends of these links are pivoted to the slips and the lower ends are pivoted to the upper shoe 17. The inclination of the links 20 is such that any pressure tending to move the shoe 17 upwardly will tend to cause the teeth 19 on the slips to firmly engage the casing. The upper surface of each of the teeth 19 is preferably at right angles to the direction of inclination of the links 20 when the slips are set. This will make it easier to release the slips by pulling them inwardly since the upper surfaces of the teeth will be tangent to the circular motion about the lower pivot points of the links.

Any known type of slip or tooth construction may be employed instead of the arrangement herein described without departing from the pur- 30 view of the invention.

The links 20 should be made as strong as possible. Since the links are intended to take chiefly compressional stresses, it is preferable to fit them into recesses or sockets in the shoe and slips, as described hereinafter in connection with Figure 35 5. As many links 20 may be employed as are necessary to give the desired strength but only two for each slip have been shown in the drawings. Being parallel, the links 20 provide means 40 for maintaining the slips in a vertical position at all times.

While the apparatus is being lowered into the well, it is desirable that the slips 18 should not drag upon the casing and it is also desirable to 45 prevent them from engaging the casing should it be desirable to raise the assembly a slight distance, as during spudding, before causing the slips to engage the casing. In accordance with the present invention, mechanism is provided 50 for accomplishing this and also for forcing the slips into tight engagement with the casing at the desired time. Connected into a socket in the upper end of each slip 18 is a short toggle link 21. These links extend upwardly and inwardly 55 to connect the slips to a control ring 22. The control ring 22 is concentrically disposed with and freely movable upon the mandrel 12. It is provided with a sleeve 23 which is temporarily 60 connected to a collar 24 fixed to the mandrel 12 by means of some suitable latch such as the latch bars 25 which extend through the wall of the mandrel 12 into the interior thereof. The latch arrangement may be as illustrated in detail in Figure 1A. The inner ends of the latch plates 25 are provided with suitable tapered portions 26 so as to cause them to move outwardly 65 radially when struck by a go-devil 27 or other suitable device which may be dropped into the well or lowered therein upon a wire line.

Instead of this means for temporarily latching the ring 22 to the mandrel, any other suitable means, such as a J-slot and pin connection, may be employed.

75 A coil spring 28 is located between the collar

24 and the ring 22 and is preferably provided with a swivel 29 at its lower end.

It will be seen that with the parts in the position in Figure 1 the slips are latched to the mandrel through the toggle links 21, the ring 22 5 and the latch plates 25 but that when these latch plates are released the spring 28 will move the ring 22 downwardly and cause the slips to move outwardly radially and engage the casing. The links 21 and the ring 22 thus constitute a toggle-joint which is capable of forcing the slips into engagement with the casing with considerable pressure and with considerable mechanical advantage when the spring 28 is released to exert a downward force on the central portion 22. Only one toggle link 21 is illustrated in connection with each slip. More could 10 obviously be employed to give strength.

In addition to the parts just described, the packer assembly includes a nut 30 screw threaded onto the mandrel 12 at a point adjacent the slips 18. The outer surface of the nut is provided with slots adapted to receive the links 20 and 21. A construction is thus provided in which the nut 30 cannot rotate with respect to the 25 slips 18. If desired, the slips may be splined to the nut to hold it against rotation but this is not shown in the drawings.

The threads on the nut are such that as the mandrel is rotated to the right, as viewed from 30 the top, the nut will travel upwardly on the mandrel. Unless the nut is splined to the slips, it must be long enough to cause the upper links 21 to enter the slots therein before the lower links 20 leave the slots so that some means is 35 always provided for holding the nut against rotation with respect to the slips.

The lower end of the nut 30 is shown provided with several depending leaf spring pawls 31 adapted to engage ratchet teeth 32 on the upper and inner surface of the shoe 17. These may be dispensed with, if desired, in which case the packer would be held expanded by pulling upwardly upon the mandrel until the cement is 40 in place.

In certain phases of the operation of the tool it is desirable to wash cement or other material out of the mandrel 12 and from and around the slips 18. To this end, wash out ports 33 are provided in the mandrel. When the nut 30 is 45 in the position shown in Figure 1, these wash out ports are closed thereby, but when the nut moves upwardly these wash out ports are opened so that fluid can flow from the inside of the mandrel through the ports and around the space 50 between the pawls 31 and upwardly between the slips 18.

The details of construction of the links 20 and 55 21 and the parts with which they are associated is shown in perspective in Figure 5. The ends of the links may be somewhat enlarged as shown at 34 to form cylindrical connecting portions adapted to fit for limited rotation within sockets 35 in the slips 18, ring 22 or shoe 17. The links may be held in position by set screws (not 60 shown) fitting into grooves in the portions 34. The nut 30 has slots 36 therein for accommodating the links 20 and 21. The slots 36 should 65 be substantially the same width as the links.

The projections 37 between the slots 36 on the 70 nut 30 may extend outwardly far enough to bring the slips 18 within the slots, in which case, it may be said that the slips are splined to the nut 30.

In accordance with the usual practice, the 75

lower shoe 14 of the assembly is provided with a suitable spring pressed valve 38.

The operation of the apparatus is as follows:

With the parts in the relative positions shown in Figure 1, the assembly is lowered into the well to the desired location. The go-devil 27 is then dropped and the ring 22 released from the mandrel so that the spring 28 forces the slip out into engagement with the casing as described above. It is to be noted that when the spring 28 is released, there will be a snap action and the slips will be forced against the casing with some impact. The parts then assume the relative position shown in Figure 2. If now the mandrel is pulled upwardly, the packer is expanded into engagement with the casing. This action takes place because the slips 18 have firmly engaged the casing. They prevent the upper shoe of the packer from moving upwardly. As the mandrel and lower shoe of the packer are pulled upwardly, the pawls 31 engage the ratchet teeth 32 and prevent the lower shoe and mandrel from moving downwardly again with respect to the upper shoe when upward pull upon the mandrel is discontinued. Thus, the packer is held in expanded position. Cement may then be forced under pressure through the drill pipe or tubing which supports the mandrel and downwardly through the mandrel passing out through the valve 34 to a point beneath the packer assembly. During the forcing of this cement downwardly through the apparatus, the fluid pressure exerted on the lower shoe of the packer will be transmitted upwardly through the packer and the upper shoe to the links 20 and the slips 18 which are then fixed to the casing.

After the desired quantity of cement has been forced into the well in this manner, the fluid pressure is relieved. The valve 38 then closes. The washing out operation may then be undertaken. To accomplish this, the drill pipe and mandrel are first rotated to the right a slight amount so as to cause the nut 36 to travel upwardly on the mandrel and open the wash out ports 33. The parts are then in the relative positions shown in Figure 3. In accordance with the usual practice, the circuit for the washing fluid, such as water, is downwardly through the drill pipe and mandrel 12 out through the wash out ports 33 and upwardly on the outside of the mandrel, around the slips 18 and upwardly between the drill pipe and the casing. Reverse circulation can be effected if desired.

The washing out operation may be continued during the entire time that it takes for the cement to harden or set, or the washing out operation may be discontinued after a time and drill pipe disconnected from the mandrel 12 and moved upwardly a sufficient distance to insure against it becoming cemented in the well. If the drill pipe is disconnected, it is later lowered and again connected on to the mandrel.

To remove the apparatus from the well, the mandrel 12 is further rotated to the right. This causes the nut to travel upwardly still further and into engagement with the ring 22 of the toggle-joint. The toggle-joint is broken as the ring 22 is forced upwardly, the spring 28 being compressed and the slips drawn radially inwardly into the position shown in Figure 4. Upon then pulling up upon the mandrel, the upper shoe of the packer may be raised, the pull being transmitted through the nut 36, the ring 22, the toggle links 21, the slips 18 and the links

20 to the upper shoe of the packer. The entire apparatus may thus be removed from the well.

While only one embodiment of the invention is shown and described herein, it is obvious that various changes may be made in the apparatus and construction of parts without departing from the spirit of the invention or the scope of the annexed claims.

I claim:

1. A packer assembly, suitable for use as a cement retainer in an oil well, which includes a packer, a set of slips located above the packer and adapted to hold the packer against upward movement when set on the casing of the well and means for setting and releasing the slips on the casing, said means including links having their outer ends connected to the slips and mechanism for actuating the inner ends of the links to cause the slips to move out and in radially in the casing. 20

2. A packer assembly, suitable for use as a cement retainer in an oil well, which includes a packer having an upper and a lower shoe, a set of slips located above the packer and adapted to hold the packer against upward movement 25 when set on the casing of the well and means for setting and releasing the slips on the casing, said means including links pivotally connecting the slips to the upper shoe of the packer and links pivotally connecting the slips to a 30 member movable with respect to the upper shoe of the packer, the arrangement being such that movement of said member with respect to the upper shoe may set and release the slips.

3. A packer assembly, suitable for use in an oil well, which includes a set of slips adapted to engage the casing of the well and means for setting and releasing said slips, said means including a toggle-joint. 35

4. A packer assembly, suitable for use as a cement retainer in an oil well, which includes a packer having an upper and a lower shoe, a set of slips located above the packer and so constructed as to resist upward movement when set on the casing of the well, means for transmitting 45 force from the upper shoe of the packer to said slips when the slips are set and mechanism having a toggle-joint therein for setting and releasing said slips.

5. An arrangement for removably fixing apparatus in the casing of an oil well including, in combination, a set of slips and mechanism for actuating the slips to move the same out and in radially of the casing, said mechanism including 50 a toggle-joint. 55

6. An arrangement for removably fixing apparatus in the casing of an oil well including, in combination, a set of slips and mechanism for actuating the slips to move the same out and in radially of the casing, said mechanism including 60 a toggle-joint adapted to set the slips upon the exertion of a downward force on the central portion thereof and adapted to release the slips upon the exertion of an upward force on the central portion thereof and means operable from the surface of the well for moving the central portion of the toggle-joint down or up with respect to the slips. 65

7. An arrangement for removably fixing apparatus in the casing of an oil well including, in combination, a set of slips and mechanism for actuating the slips to move the same out and in radially of the casing, said mechanism including 70 a toggle-joint adapted to set the slips upon the exertion of a downward force on the central portion thereof and adapted to release the slips upon the exertion of an upward force on the central portion thereof and means operable from the surface of the well for moving the central portion of the toggle-joint down or up with respect to the slips. 75

- tion thereof and adapted to release the slips upon the exertion of an upward force on the central portion thereof and means operable from the surface of the well for moving the central portion 5 of the toggle-point down or up with respect to the slips, said means including a member screw threaded to a pipe and adapted upon rotation of the pipe to move the central portion of the toggle-joint in one direction.
- 10 8. An arrangement for removably fixing a packer in the casing of an oil well including, in combination, a set of slips, links connecting the slips to the packer so as to permit the slips to move in and out radially with respect to the packer and 15 a toggle-joint for controlling the radial movement of the slips.
9. An arrangement for removably fixing a packer in the casing of an oil well including, in combination, a mandrel for carrying the packer, a 20 set of slips, links connecting the slips to the packer so as to permit the slips to move in and out radially with respect to the packer, toggle-joint mechanism for controlling the radial movement of the slips and means screw threaded on 25 the mandrel for moving the toggle-joint mechanism in one direction.

10. An arrangement for removably fixing a packer in the casing of an oil well including, in combination, a mandrel for carrying the packer, a set of slips, links connecting the slips to the packer so as to permit the slips to move in and out radially with respect to the packer, toggle-joint mechanism for controlling the radial movement of the slips, means screw threaded on the mandrel for moving the toggle-joint mechanism in one direction and a spring for urging the toggle-joint mechanism in another direction. 10

11. An arrangement for removably fixing a packer in the casing of an oil well including, in combination, a mandrel for carrying the packer, a set of slips, links connecting the slips to the 15 packer so as to permit the slips to move in and out radially with respect to the packer, toggle-joint mechanism for controlling the radial movement of the slips, means screw threaded on the mandrel for moving the toggle-joint mechanism 20 in one direction, a spring for urging the toggle-joint mechanism in another direction and means for temporarily latching said spring and toggle-joint mechanism to the mandrel to hold the same in fixed position with respect thereto. 25

PAUL M. ROHRBAUGH.
